AMPLITUDE MODULATION

Russell R. Law, Princeton, N. J., assignor to Radio Corporation of America, a corporation of Delaware

Application December 21, 1948, Serial No. 66,542

12 Claims. (Cl. 332—63)

1

This invention relates to amplitude modulation, and more particularly to a modulator for a radio frequency amplifier.

An object of this invention is to devise a modulator circuit which will give a greater depth of modulation, or a larger change of power, in a radio frequency power amplifier, than that given by circuits used heretofore, for a given modulation signal.

Another object is to devise a circuit including a radio frequency amplifier and a modulator so interconnected that there is a substantially constant flow of direct current to the cathodes and therefore also to the anodes of the modulator and the amplifier, the direct current being switched from the amplifier tube to the modulator tube, and vice versa at the modulating frequency, when a modulating signal is applied, to produce modulation of the radio frequency carrier.

The foregoing and other objects of the invention will be best understood from the following description of some exemplifications thereof, reference being had to the accompanying drawing, wherein:

Fig. 1 is a rather detailed diagrammatic representation of the basic circuit of this invention; and

Fig. 2 is a somewhat simplified schematic diagram of a practical embodiment of this invention.

Now referring to Fig. 1, a suitable source of modulating signals, such as video signals for example, is connected to input terminals 1 and 2, terminal 2 being grounded as shown. Terminal 1 is connected directly to the control grid 3 of a triode 4 which serves as a video modulator. Triode 4 may be, and preferably is, a coaxial-cavity triode of the type described in detail in the article by Law et al., RCA Review, volume VII, No. 2, June 1946, pages 253-264. Electron discharge device 4 includes, in addition to grid 3, a cathode 5 and an anode 6. A suitable source 7 of variable bias has one output terminal grounded and its opposite terminal connected through a resistor 8 to terminal 1 and grid 3, to suitably bias said grid.

Anode 6 is grounded for radio frequencies through condenser 9, and is also connected to the positive terminal of a D.-C. or B power supply 10, the negative terminal of which is grounded as shown. Cathode 5 of tube 4 is connected directly to a point 11 which will be referred to later.

Tube 4 is used to cathode-modulate a grounded-grid triode or electron discharge device 12 which thus operates as a cathode-modulated radio frequency power amplifier. This triode preferably is of the coaxial-cavity type described in the Law et al. article, "A developmental television transmitter for 500-900 megacycles," published in RCA Review, volume IX, No. 4, December 1948, pages 643-652, and includes an anode cavity 12a and a cathode cavity 12b, separated

5 by a metallic partition 12c which includes the control grid 13 of the triode 12. Grid 13 is grounded at 14. Cathode 15 of electron discharge device 12 is connected through an opening in cavity 12b to point 11, while anode 16 of said device is connected through an opening in cavity 12a to the positive terminal of power supply 10, said anode being grounded for alternating currents through condenser 11. The lead to the cathode 15 and the lead to the anode 16 are illustrated as passing through the usual R-F choke apertures into the respective cavities, the cathode being therefore bypassed or grounded to the cavity for R-F only.

10 R-F input energy from a suitable source, not shown, is applied to the R-F power amplifier including tube 12 by means of a coaxial line 18, the inner conductor of which terminates in a coupling loop 19 electromagnetically coupled into cathode cavity 12b. Modulated R-F output energy is abstracted from the R-F power amplifier by means of a coaxial line 20, the inner conductor of which terminates in a coupling loop 21 electromagnetically coupled into anode cavity 12a.

15 According to this invention, bias is supplied to the two tubes 12 and 14 by connecting the positive terminal of a D.-C. bias source 22 through a constant-current network 23 to the common cathode point or terminal 11. Network 23 is illustrated as an inductance which is split into sections 23a, 23b and 23c of progressively increasing size, for a reason which will hereinafter appear. The negative terminal of current source 22 is grounded at 24 to complete the D.-C. anode-cathode circuit to the negative terminal of power supply 10. Source 22 biases cathodes 5 and 15 positively with respect to ground or with respect to grounded grid 13. Bias source 7 is so 20 adjusted that cathode 5 is also positive with respect to grid 3.

25 Ordinarily, the grounded-grid triode 12 is operated under Class C conditions to give good efficiency, said triode therefore operating as a Class C grounded-grid amplifier. Under Class C conditions, the instantaneous cathode potential swings below the grid potential level or ground, so that the grid is effectively positive with respect to the cathode, for only a fraction of the cycle of R-F applied voltage, and during this fraction a momentary pulse of current is drawn from the cathode 15 and injected into the grid-anode space. If the instantaneous anode potential is below the D.-C. value thereof when this pulse of current arrives at the anode, a portion of the D.-C. power from source 10 is converted into A.-C. energy, thus providing amplification of the R-F input energy.

30 Therefore, the power level of the R-F output appearing in lead 20 varies in the same direction as, and substantially proportionally to, the level of the D.-C. power applied from sources 10 and 22 (these two sources being effectively in

series in the anode-cathode circuit of tube 12) to tube 12. Such D.-C. power is substantially directly proportional to the product of plate voltage and plate current in this tube, so that as the direct plate current of tube 12 is increased, the power level of the R-F output in lead 20 is increased also. Thus, by variation or modulation of the D.-C. anode current to tube 12, amplitude modulation of the R-F carrier is produced, this modulated R-F carrier appearing in lead 20.

This action may be explained in another way, as follows: When the positive bias, with respect to ground or grid 13, on cathode 15 is increased, the duration of the momentary pulse of current drawn from cathode 15 and injected into the grid-anode space of tube 12 is decreased (because the time during which the instantaneous cathode potential is below the grid potential level is lessened), thus decreasing the portion of the D.-C. power which is converted into A.-C. energy and also decreasing the level of the R-F output power. Conversely, when the positive bias (with respect to ground) on cathode 15 is decreased, the R-F output power is increased.

In operation, the bias source 22 is so adjusted as to give the desired sum-total direct current to the cathodes 5 and 15 of the modulator 4 and amplifier 12, this total being appropriate to the particular characteristics of the tubes utilized. Inasmuch as this current flows through the series-connected inductances 23a, 23b and 23c, video frequency changes in current are substantially prevented by the "flywheel" effect of the inductance, and the combined direct currents to the modulator 4 and amplifier 12 will remain substantially constant. The inductance 23 is chosen so as to have practically no D.-C. resistance, the current drawn through said inductance being substantially constant through its inherent action; the inductance 23 may therefore be termed a constant-current network.

The current flowing from source 22 to the two cathodes 5 and 15 is held substantially constant by the action of inductance 23, the division of current between the two cathodes depending on the character of the modulations. When a positive modulating signal is impressed on the grid 3 of the modulator 4, an increased flow of current through the modulator tube results, but, inasmuch as the total current from source 22 is held constant by the action of network 23, the current to the cathode 15 of amplifier 12 is reduced, reducing also the R-F output power in lead 20. Conversely, a negative signal applied to grid 3 has the effect of decreasing the current taken by modulator 4 and thereby increasing the current delivered to the amplifier 12, increasing the R-F output power in lead 20. Thus, amplitude modulation of the R-F carrier is produced.

In effect, then, the sum of the direct currents to the two cathodes 5 and 15 from source 22 and/or source 10 is held constant; this also holds the direct current to the two anodes substantially constant. Modulation at video frequencies serves to switch the current from the amplifier 12 to the modulator 4 and vice versa.

The advantages of using a constant-current network in the common bias lead to the cathodes 5 and 15 should now become apparent. If an impedance in which an IR voltage drop could occur, and in which the series current could change, were used in the common cathode bias lead, the current change in the R-F power amplifier tube produced as a result of modulation would not be as great as that which is produced

by modulation when a constant current network is used in the common cathode bias lead. To make this clearer, assume that a series resistance of ten ohms is in the common cathode bias lead, and that a current of one ampere is flowing to cathode 5 and a current of one ampere to cathode 15. Thus, two amperes of current are flowing through the resistor, giving an IR drop of twenty volts therein, biasing the two cathodes twenty volts positive with respect to ground. If, now, a modulating signal is applied to grid 3 such that the current to cathode 5 goes to zero, the current to cathode 15 remains substantially one ampere and the IR voltage drop in the series bias resistor falls to ten volts. This change in the IR drop or cathode bias, from twenty volts to ten volts, would at first glance seem to be sufficient to produce a maximum change of current in R-F amplifier tube 12, and therefore also a maximum amount of amplitude modulation of the R-F carrier. However, the plate current-bias characteristic curve of a triode such as triode 12 is nonlinear and does not have a slope such that when the bias is halved the current is doubled. Therefore, the ratio of the currents in the R-F amplifier tube with the series resistor circuit connection is substantially less than one-to-two from the initial situation above to the final situation above, giving a less than maximum amount of amplitude modulation of the R-F carrier.

If, now, instead of a series resistor in the cathode bias lead, a constant-current network is used in this lead, when the one ampere of current originally flowing to cathode 5 is reduced to zero in response to a modulating signal, this one ampere of current is added to the one ampere flowing to cathode 15, making a total of two amperes flowing thereto. This is so because with a constant-current network in series in the cathode bias lead, the total D.-C. flowing is maintained substantially constant at its original value of two amperes and cannot change in response to modulating signals. Thus, with the constant-current circuit connection, the ratio of the current in the R-F amplifier tube is substantially one-to-two from the initial situation to the final situation, giving the maximum possible change of power in the R-F amplifier or the maximum possible amount of amplitude modulation of the R-F carrier.

The reason for splitting the series inductance 23 into sections 23a, 23b and 23c of progressively increasing size or progressively increasing inductance is to provide relatively high impedance over the video band. In a practical embodiment, section 23c was a large iron-core filter choke of the kind commonly used in 60-cycle rectifier power supplies. Sections 23b and 23a were successively smaller coils designed to resonate at successively higher frequencies. Thus, 23b had an inductance such that, in combination with its distributed capacitance, resonance occurred at approximately one-half megacycle, while 23a in turn had an inductance such that in combination with its distributed capacitance resonance occurred at approximately 20 megacycles. Tests of this combination indicated an impedance of many thousands of ohms throughout the entire video band. So long as this impedance is large compared to $R_p/1+\mu$, the gain is substantially constant and equal to $\mu/1+\mu$, where R_p and μ refer to the characteristics of triode 12. The high value of impedance of the combination 23a, 23b, 23c is so

large as to give substantially constant gain as just defined.

Now referring to Fig. 2, which shows a practical embodiment of this invention, parts the same as those of Fig. 1 are referred to by the same reference numerals. Video input signals are applied to the control grid 25 of a triode 26 which is cathode-coupled to the two parallelly-connected modulator triodes 4 and 4'. Anode 27 of triode 26 is connected to a positive source of D.-C. potential through a resistor 28, and is by-passed to ground for radio frequencies by a condenser 29. Cathode 30 of triode 26 is connected directly to the two grids 3 and 3' of modulator triodes 4 and 4', a suitable bias being applied thereto through resistor 8. The cathode-coupled stage 26 ahead of the modulator triodes 4 and 4' serves to lower the effective input capacitance presented to the video amplifier by the set of tubes 4 and 4', this cathode follower stage 26 having a low input capacitance.

The two modulator tubes 4 and 4' are connected in parallel, having their grids 3 and 3' connected to cathode 30, as previously described, and having their cathodes 5 and 5' connected together and to a point 11.

A resistor 31 is connected in series with anode 6, from it to the positive potential source, while a resistor 32 is connected in series with anode 6', from it to the positive potential source, these resistors, as well as resistor 28 in series with anode 27, being provided for the purpose of suppressing parasitic oscillations. The plate ends of resistors 31 and 32 are carefully by-passed to ground by mica condensers 9 and 9' of several microfarads capacitance, the condenser 29 similarly by-passing the plate end of resistance 28 to ground.

As in Fig. 1, a positive bias is supplied to point 11 through a constant-current network or inductance 23. Although in Fig. 2 the inductance is shown as a single section, it is desired to be made clear that actually inductance 23 is split into a plurality of sections, as previously described in connection with Fig. 1.

A pair of triodes 12 and 12' are connected in push-pull to serve as an R-F power amplifier, point 11 being connected to the nodal point of a U-shaped conductor which connects cathodes 15 and 15'. Grids 13 and 13' are connected together and to ground at 14, while the direct current lead to the anodes 16 and 16' is led off from the nodal point of a U-shaped conductor connecting these anodes. A condenser 17 by-passes the anodes to ground for alternating currents, while R-F input energy is applied by means of line 18, modulated R-F output being abstracted by means of line 20 as in Fig. 1.

Operation of the circuit of Fig. 2 is substantially similar to that previously described in connection with Fig. 1, the inductance 23 again functioning as a constant-current network to provide the advantages previously described in detail above. As an example, a current change of more than two amperes in the R-F amplifier tubes 12 and 12' was obtained by the scheme of modulation disclosed in Fig. 2. When a positive modulating signal is impressed on the first tube 26, the cathode 30 of this tube becomes more positive due to the drop of the biasing voltage developed across resistor 8 due to increased current flow in tube 26. This increases the positive voltage on the grids 3 and 3' of the modulator tubes and results in an increased flow of current therein. But, since the total current is held constant by

the action of inductance 23, the current to the amplifier tubes 12 and 12' is reduced, giving a reduced R-F power output in lead 20. Conversely, a negative signal applied to the first triode 26 has the effect of decreasing the current taken by the modulator tubes 4 and 4', thereby increasing the current delivered to the amplifier tubes 12 and 12' and increasing the R-F power output in lead 20. Thus, amplitude modulation of the R-F carrier is produced.

Although it is to be understood that this invention is not to be limited thereto, the following rather typical values are given for an operative embodiment of this invention. D.-C. bias on the commonly-connected cathodes 5 and 15 was 80 volts positive with respect to ground. In view of the high transconductance of the modulator tube, approximately 0.15 ampere per volt at the operating point, the voltage difference between the control grid 3 and cathode 5 of the modulator tube is only a few volts. Thus, the cathode 30 of the preceding stage is only a few volts more negative than the conjoined cathodes of the modulator and amplifier. The value of resistor 8 for this first stage is determined by the impedance band width requirements required to match the output of the preceding video amplifier. With a resistor 8 of approximately 100 ohms in the case of current of 0.5 ampere, a bias supply of approximately -40 volts is required for this tube 26. All stages of the circuit operate from a common anode supply which was operated at from 800 to 1,000 volts. Each of the resistors 28, 31, and 32 has a value of approximately 10 ohms, the condensers 9, 9' and 29 being mica condensers each of several microfarads capacitance.

From all of the above, it will be seen that the objects of the invention have been accomplished. With the circuit of this invention, a maximum depth of amplitude modulation of an R-F carrier has been achieved by cathode modulation of an R-F power amplifier, this being accomplished through switching of the direct cathode current from the modulator tube to the amplifier tube, and vice versa, at modulating frequencies and in response to modulating signals applied to the input of the modulating system.

What I claim as my invention is:

1. In a transmitting system: a high frequency stage to be modulated, said stage including an electron discharge device having at least a cathode and an anode, variation of the anode-cathode current flow causing modulation of the high frequency carrier applied to such stage; a modulator stage, said last-named stage including an electron discharge device having a cathode, an anode, and a control electrode; means for applying modulating signals to said control electrode to vary the anode-cathode current flow in said last-named device; means connecting the cathodes of said devices together and the anodes of said devices together in order to cathode-modulate said high frequency stage; means connecting the anodes of said devices to a source of positive potential; a common circuit for connecting both of the cathodes to a single source of current which supplies current to both cathodes; and means in said common circuit for maintaining substantially constant the total current flow in the two devices.

2. In a transmitting system: a high frequency stage to be modulated, said stage including an electron discharge device having at least a cathode and an anode, variation of the anode-cathode current flow causing modulation of the

high frequency carrier applied to such stage; a modulator stage, said last-named stage including an electron discharge device having a cathode, an anode, and a control electrode; means for applying modulating signals to said control electrode to vary the anode-cathode current flow in said last-named device; means connecting the cathodes of said devices together and the anodes of said devices together in order to cathode-modulate said high frequency stage; means connecting the anodes of said devices to a source of positive potential; a common circuit for connecting both of the cathodes to a single source of current which supplies current to both cathodes; and a constant-current network connected in series in said common circuit to maintain substantially constant the total current flow in the two devices.

3. In a transmitting system: a high frequency stage to be modulated, said stage including an electron discharge device having at least a cathode and an anode, variation of the anode-cathode current flow causing modulation of the high frequency carrier applied to such stage; a modulator stage, said last-named stage including an electron discharge device having a cathode, an anode, and a control electrode; means for applying modulating signals to said control electrode to vary the anode-cathode current flow in said last-named device; means connecting the cathodes of said devices together and the anodes of said devices together in order to cathode-modulate said high frequency stage; means connecting the anodes of said devices to a source of positive potential; a common circuit for connecting both of the cathodes to a single biasing source of current which supplies current and biasing voltage to both cathodes; and means in said common circuit for maintaining substantially constant the total current flow in the two devices.

4. In a transmitting system: a high frequency stage to be modulated, said stage including an electron discharge device the flow of current through which may be varied to modulate the high frequency carrier applied to such stage; a modulator stage, said last-named stage including an electron discharge device the flow of current through which may be varied by modulating signals; means for applying modulating signals, the frequencies of which may vary over a band, to said last-named device to vary the flow of current therethrough; a common circuit for connecting both of said devices to a single source of current which supplies current to both devices; and an inductance connected in series in said common circuit to maintain substantially constant the total current flow in the two devices, said inductance being split into a plurality of sections of different inductance values to provide a high impedance throughout the band of frequencies of said signals.

5. A modulating system, comprising a first electron discharge device having input electrodes and output electrodes, means for applying modulating signals to said input electrodes, a second electron discharge device having an anode, a cathode, and a control electrode, means for applying high frequency carrier energy to said second device and for abstracting modulated high frequency energy therefrom, means connecting the output electrodes of said first device to the cathode and anode of said second device in order to effect cathode-modulation of said carrier energy by means of said second device, means connecting said control electrode to a point of reference potential, means connecting the anodes of said first

and second devices to a source of positive potential, a common circuit for connecting the cathodes of said first and second devices to a single source of current and bias voltage which biases said cathodes positively with respect to said reference potential, and means in said common circuit for maintaining substantially constant the total current flow to the cathodes of said two devices.

10 6. A modulating system, comprising a first electron discharge device having input electrodes and output electrodes, means for applying modulating signals to said input electrodes, a second electron discharge device having an anode, a cathode, and a control electrode, means for applying high frequency carrier energy to said second device and for abstracting modulated high frequency energy therefrom, means connecting the output electrodes of said first device to the cathode and anode of said second device in order to effect cathode-modulation of said carrier energy by means of said second device, means connecting said control electrode to a point of reference potential, means connecting the anodes of said first and second devices to a source of positive potential, a common circuit for connecting the cathodes of said first and second devices to a single source of current and bias voltage which biases said cathodes positively with respect to said reference potential, and a constant-current network connected in series in said common circuit to maintain substantially constant the total current flow to the cathodes of said two devices.

7. A modulating system, comprising a first electron discharge device having input electrodes and output electrodes, means for applying modulating signals, the frequencies of which may vary over a band, to said input electrodes, a second electron discharge device having an anode, a cathode, and a control electrode, means for applying high frequency carrier energy to said second device and for abstracting modulated high frequency energy therefrom, means connecting the output electrodes of said first device to the cathode and anode of said second device in order to effect cathode-modulation of said carrier energy by means of said second device, means connecting said control electrode to a point of reference potential, means connecting the anodes of said first and second devices to a source of positive potential, a common circuit for connecting the cathodes of said first and second devices to a single source of current and bias voltage which biases said cathodes positively with respect to said reference potential, and an inductance connected in series in said common circuit to maintain substantially constant the total current flow to the cathodes of said two devices, said inductance having a high impedance throughout the band of frequencies of said signals and having a low D.-C. resistance.

8. A modulating system, comprising a first electron discharge device having input electrodes and output electrodes, means for applying modulating signals, the frequencies of which may vary over a band, to said input electrodes, a second electron discharge device having an anode, a cathode, and a control electrode, means for applying high frequency carrier energy to said second device and for abstracting modulated high frequency energy therefrom, means connecting the output electrodes of said first device to the cathode and anode of said second device in order to effect cathode-modulation of said carrier energy by means of said second device, means connecting

necting said control electrode to a point of reference potential, means connecting the anodes of said first and second devices to a source of positive potential, a common circuit for connecting the cathodes of said first and second devices to a single source of current and bias voltage which biases said cathodes positively with respect to said reference potential, and an inductance connected in series in said common circuit to maintain substantially constant the total current flow to the cathodes of said two devices, said inductance being split into a plurality of sections of different inductance values to provide a high impedance throughout the band of frequencies of said signals.

9. A modulating system, comprising a first electron discharge device having an anode, a cathode, and a control electrode, means for applying modulating signals to said control electrode, a second electron discharge device having an anode, a cathode, and a control element, means coupling said control element to the cathode of said first device in order to control the flow of current in said second device by said signals, a third electron discharge device having an anode, a cathode, and a control grid, means for applying high frequency carrier energy to said third device and for abstracting modulated high frequency energy therefrom, means connecting the cathodes of said second and third devices together, means connecting the anodes of each device to a source of positive potential in order to effect cathode-modulation of said carrier energy by means of said third device, means connecting said control grid to a point of reference potential, a common circuit for connecting the cathodes of said second and third devices to a single source of current and bias voltage which biases said two last-named cathodes positively with respect to said reference potential, and means in said common circuit for maintaining substantially constant the total current flow to said two last-named cathodes.

10. A modulating system, comprising a first electron discharge device having an anode, a cathode, and a control electrode, means for applying modulating signals to said control electrode, a second electron discharge device having an anode, a cathode, and a control element, means coupling said control element to the cathode of said first device in order to control the flow of current in said second device by said signals, a third electron discharge device having an anode, a cathode, and a control grid, means for applying high frequency carrier energy to said third device and for abstracting modulated high frequency energy therefrom, means connecting the cathodes of said second and third devices together, means connecting the anodes of each device to a source of positive potential in order to effect cathode-modulation of said carrier energy by means of said third device, means connecting said control grid to a point of reference potential, a common circuit for connecting the cathodes of said second and third devices to a single source of current and bias voltage which biases said two last-named cathodes positively with respect to said reference potential, and a constant-current network connected in series in said common circuit to maintain substantially constant the total current flow to said two last-named cathodes.

11. A modulating system, comprising a first electron discharge device having an anode, a cathode, and a control electrode, means for applying modulating signals, the frequencies of which may vary over a band, to said control elec-

trode, a second electron discharge device having an anode, a cathode, and a control element, means coupling said control element to the cathode of said first device in order to control the flow of current in said second device by said signals, a third electron discharge device having an anode, a cathode, and a control grid, means for applying high frequency carrier energy to said third device and for abstracting modulated high frequency energy therefrom, means connecting the cathodes of said second and third devices together, means connecting the anodes of each device to a source of positive potential in order to effect cathode-modulation of said carrier energy by means of said third device, means connecting said control grid to a point of reference potential, a common circuit for connecting the cathodes of said second and third devices to a single source of current and bias voltage which biases said two last-named cathodes positively with respect to said reference potential, and an inductance connected in series in said common circuit to maintain substantially constant the total current flow to said two last-named cathodes, said inductance having a high impedance throughout the band of frequencies of said signals and having a low D.-C. resistance.

12. A modulating system, comprising a first electron discharge device having an anode, a cathode, and a control electrode, means for applying modulating signals, the frequencies of which may vary over a band, to said control electrode, a second electron discharge device having an anode, a cathode, and a control element, means coupling said control element to the cathode of said first device in order to control the flow of current in said second device by said signals, a third electron discharge device having an anode, a cathode, and a control grid, means for applying high frequency carrier energy to said device and for abstracting modulated high frequency energy therefrom, means connecting the cathodes of said second and third devices together, means connecting the anodes of each device to a source of positive potential in order to effect cathode-modulation of said carrier energy by means of said third device, means connecting each of said anodes to ground for frequencies on the order of the frequency of said carrier energy, means connecting said control grid to a point of reference potential, a common circuit for connecting the cathodes of said second and third devices to a single source of current and bias voltage which biases said two last-named cathodes positively with respect to said reference potential, and an inductance connected in series in said common circuit to maintain substantially constant the total current flow to said two last-named cathodes, said inductance being split into a plurality of sections of different inductance values to provide a high impedance throughout the band of frequencies of said signals.
